Primary Examiner — Kevin Rudzinski(74) *Attorney, Agent, or Firm* — Rosenberg, Klein & Lee(57) **CLAIM**

The ornamental design for an LED lamp, as shown and described.

DESCRIPTION

FIG. 1 is a perspective view of an LED lamp showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a perspective view showing the LED lamp with a hanging ring.

FIG. 9 is a perspective view showing the LED lamp with a connector connected with two strings; and,

FIG. 10 is a perspective view showing the LED lamp with a hanging stick.

The broken lines shown in the drawings illustrate environmental structure and form no part of the claimed design.
